UNITED STATES PATENT OFFICE.

EDWARD L. CANON, OF QUITMAN, GEORGIA, ASSIGNOR OF ONE-HALF TO THOMAS E. JOHNSON, OF QUITMAN, GEORGIA.

GATE.

1,231,704.

Specification of Letters Patent.

Patented July 3, 1917.

Application filed November 16, 1916. Serial No. 131,705.

To all whom it may concern:

Be it known that I, EDWARD L. CANON, a citizen of the United States, residing at Quitman, in the county of Brooks and State 5 of Georgia, have invented certain new and useful Improvements in Gates, of which the following is a specification.

This invention relates to a gate and more particularly to a gate which may be employed as a closure for the gate opening in 10 fences upon farms and the like, although the construction of the gate is such that it may be employed for this purpose in connection with other openings, if found desirable.

The primary object of the invention is to provide a gate of this character in which a barrier for closing the gate opening is mounted for vertical sliding movement 20 within guide posts, and is supported in such position by mechanism connected therewith for holding the barrier in active position, and having connected therewith a platform arranged within the gateway to be depressed 25 under the weight of the vehicle or the like to cause the barrier to be moved to an inactive position, and retained in such position until the vehicle passes through the gate opening and from the platform, at which 30 time the barrier will again assume its normal or active position.

Another object of the invention is to provide a gate of this character in which the mechanism for supporting and normally 35 holding the barrier in an active position to close the gate opening may be arranged in a pit between the gate posts, and in which the gate is received when moved to an inactive position by the weight of a load upon 40 said platform which serves as a cover for said pit, thus placing said mechanism in an out-of-the-way position and protecting the same from the weather.

A further object of the invention is to 45 provide the gate with a barrier, the frame of which extends within guideways in the guide posts and has hingedly connected therewith cross strips also having hinged connection with the weight-controlled barrier-carrying frames mounted for tilting 50 movement within the pit and supporting the load operated platform, through the operation of which the barrier-carrying frames may be tilted and the barrier moved through

a slot in said platform into the pit and 55 retained therein until the load has been moved from the platform.

A still further object of the invention is to provide the barrier-carrying frames with a barrier in which a frame forming a part 60 of the same and having its side rails received in guideways in the guide posts has one side rail thereof so constructed that when the barrier is in an active position for closing the gate opening, the said rail may 65 be engaged by the locking head on a latch arranged within an opening in one of the guide posts and engageable with the rail to lock the barrier in an active position.

With these and other objects in view, the 70 invention resides in the novel combination and arrangement of parts which will be hereinafter described and particularly pointed out in the claim.

The preferred embodiment of the invention 75 has been illustrated in the accompanying drawings, although no restriction is necessarily made to the precise details of construction therein shown, as changes, alterations and modifications within the scope 80 of the claim may be resorted to when desired.

In the drawings,—

Figure 1 is a perspective view showing the improved gate with parts broken away arranged in a gateway and closing the gate 85 opening in a fence.

Fig. 2 is a top plan view of the gate with the platform removed.

Fig. 3 is a longitudinal sectional view on 90 the line 3—3 of Fig. 2, the barrier and operating mechanism connected therewith being shown in raised position in full lines and in lowered position in dotted lines.

Fig. 4 is a vertical transverse sectional 95 view on the line 4—4 of Fig. 3.

Fig. 5 is a similar view on the line 5—5 of Fig. 3.

Like characters of reference denote corresponding parts throughout the several 100 views.

Referring now to the drawings in detail, the letter A designates a portion of the fence having formed therein a gate opening B to be normally closed by the improved 105 gate C arranged within a pit D in the roadway passing between the gate posts E. The pit D is preferably lined with cement, and

has arranged in the bottom thereof a siphon 7 for draining purposes, and has formed therein adjacent each end a pair of spaced supports 8 upon which are arranged plates 9 having extending transversely thereof bearing ribs 10 triangular in shape in cross-section to provide each rib with a knife edge 11.

A pair of barrier-carrying frames 12 and 13, which are rectangular in shape to provide each frame with side bars 14 and end bars 15 and 16, are arranged within the pit D above the supports 8, and with the end bars 16 of the frames arranged in opposed relation, said frames having connected with the under faces of the side bars 14 adjacent the end bars 15 bearings 17 having formed therein transversely extending openings 18, V-shaped in cross section and receiving therein the ribs 10, so that the frames 12 and 13 rest upon the knife edges 11 of the ribs and are free to tilt thereon.

The tilting movement of the frames 12 and 13 upon the ribs 10 is limited by the inclined walls of the openings 18, while lateral movement of the frames upon the supports is prevented by flanges 19 on the bearings 17 engaging the inner ends of the ribs 10 above the plates 9.

The end bars 18 of the barrier-carrying frames are substantially L-shaped in cross section with the vertically extending portions of the bars curved in opposite directions and provided at intervals throughout their length with elongated and longitudinally extending slots 20, the purpose of which will hereinafter appear.

Extending transversely of each barrier-carrying frame and mounted to turn in bearings 21 on the side bars thereof adjacent the bearings 17 is a crank shaft 22, the ends of which extend beyond the side bars 14 and are bent downwardly and outwardly to provide cranks 23. A platform carrying frame 24 is arranged within the pit D, and has secured to the under face of the side rails 25 thereof bearings 26 having jaws 27 thereon receiving therebetween the cranks 23 upon which the frame 24 rests, so that as the frames 12 and 13 tilt on the ribs 10, the shafts 22 will enable the frame 24 to remain in a horizontal position.

The side bars 25 of the frame 24 have secured thereto vertically extending guide posts 28 aligned with the gate posts E, and having formed in their confronting faces longitudinally extending grooves forming guideways 29 slidably receiving therein the side bars 30 of a barrier frame 31 having a top rail 32 and a bottom rail 33. The frame 31 has arranged upon opposite sides thereof vertically extending strips 34, the upper ends of which are rolled to form eyes 35 having passed therethrough the top rail 32, while the lower ends of the strips upon each side of the frame are oppositely curved to

form fingers 36 loosely passing through the slots 20 in the curved portions of the end bars 16 to hingedly connect the strips therewith, so that when the barrier-carrying frames are tilted to the position shown in dotted lines in Fig. 3, the barrier will be slid downwardly and within the pit D. The lower rail of the barrier frame has mounted to turn thereon a sleeve 37 to be engaged by the end bars 16 when the barrier is in active position. Arranged within the pit D between the supports 8 are a pair of bars 38 having hinged connection with the end walls of the pit and adjustably mounted between their ends in yokes 39 swingingly connected with the end bars 15 of the barrier-carrying frames and having adjustably mounted thereon weights 40 normally serving to counter-balance the weight of the platform-carrying frame and to hold the barrier-carrying frames in a tilted position in which the barrier 41 formed by the frame and strips 35 is held in a raised or active position above the platform-carrying frame 24.

A platform 42, by means of which when a load is placed thereon the barrier-carrying frames may be tilted in the reverse direction against the influence of the weights 40 to move the barrier to an inactive position within the pit D, is arranged upon the platform-carrying frame 24, and comprises a pair of primary treads 43 partially supported upon the ends of the frame 24 and fulcrumed on bearing flanges 44 on the end walls of the pit and receiving therebetween supplemental treads 45 arranged upon opposite sides of the guide posts 28, and between which and the inner ends of the supplemental treads are arranged cross strips 46 forming within the platform 42 a barrier receiving opening 47. The supplemental treads 45 are held against displacement upon the platform carrying frame by fingers 48 engaging the cross strips 46.

Through the above described manner of constructing the platform 42 and mounting the frame thereof upon the cranks of the shafts 22, it will be seen that when the platform is depressed under the weight of a vehicle or the like, the primary treads 43 tilt, while the supplemental treads and the platform-carrying frame remain in a horizontal position under all conditions.

A latch 49 is pivotally mounted within an opening in one of the guide posts 28, and is provided with a locking head 50 extending within the guideway therein and engageable with notches 51 in one of the side bars 30 of the barrier frame to lock the barrier in a raised or active position, said latch being provided with an operating arm 52 extending exteriorly of the post and having passed therethrough a pin 53 engageable with the post to normally hold the latch in an inactive position.

When the improved gate is arranged within a roadway, as shown in Fig. 1 of the drawing, it will be seen that a vehicle or the like if driven upon the platform 40 will depress the same and counterbalance the weights 40 and rock the barrier-carrying frames upon the supports 8 to move the barrier in a downward direction and within the pit D in which the barrier will be retained below the platform 42 until the vehicle has passed through the guideway and left the platform, at which time the weights 40 will again counterbalance the weight of the platform and frame thereof and tilt the barrier-carrying frames in the reverse direction to raise the barrier to its normal or active position above the platform 42 in which position the barrier closes the gate opening.

From the foregoing description, taken in connection with the accompanying drawings, it is apparent that a weight-controlled load-operated gate has been provided which is simple in construction, inexpensive of manufacture and thoroughly efficient in use.

Having thus described the invention, what 25 is claimed as new, is:

A gate comprising a pair of frames mounted to tilt within a pit, a vertically movable barrier interposed between said frames, pivoted cross strips on said barrier 30 having hinged connection with said frames whereby the barrier may be raised and lowered thereby, yokes on said frames, pivoted and weighted bars adjustably mounted in said yokes to normally hold said barrier in a 35 raised position, a frame swingingly supported on said pair of frames and having guide posts receiving the ends of the barrier, supplemental treads on said frame operable under the influence of a load to act in 40 opposition to said bars, and primary treads mounted to tilt on said frame.

In testimony whereof I affix my signature in the presence of two witnesses.

EDWARD L. CANON.
